MELVIN A. MILLS, OF LAWRENCE, MASSACHUSETTS.

BEATING-ENGINE.

SPECIFICATION forming part of Letters Patent No. 726,726, dated April 28, 1903.

Application filed August 2, 1901. Serial No. 70,637. (No model)

To all whom it may concern:

Be it known that I, MELVIN A. MILLS, a citizen of the United States, residing at Lawrence, in the county of Essex and State of Massachusetts, have invented an Improvement in Beating-Engines, of which the following description, in connection with the accompanying drawings, is a specification, like characters on the drawings representing like parts.

This invention relates to what are known as "beating-engines," which are used for disintegrating and mixing the material for the preparation of paper-stock; and it is the object of my invention to provide an engine which is capable of taking care of an increased amount of stock and which requires a less expenditure of power than beating-engines as commonly constructed.

In one familiar type of beating-engines the pulp-tub is divided by a mid-feather into two parallel circulating-channels, and in one of said channels is the beating-roll having disintegrating-blades on its periphery which operate with a bed-plate in the bottom of the channel. These rolls are commonly mounted on shafts which are supported above the pulp-tub, so that only the lower half of the roll is immersed in the stock, and to provide for the proper circulation of the stock a backfall is placed in the channel immediately adjacent the delivery side of the roll, said backfall coming nearly to the top of the channel. The stock as it is disintegrated between the blades and the bed-plate is carried by the blades and delivered over the top of the backfall and is then acted on by gravity and carried around the circulating-channel to the feed side of the roll. In this type of engine the friction between the blades and the bed-plate creates a resistance to the rotation of the roll, which resisting force is applied at the end of the radius of the roll, and because the roll is of such a large diameter the lever-arm of of this resisting force is correspondingly long, and a correspondingly great power is necessary to overcome the same. Furthermore, added power is necessary to lift the stock over the backfall, such lifting force also being applied at the periphery of the roll. It will be obvious that if the roll were made smaller the lever-arm of the resisting force

would be correspondingly shortened, and less power would consequently be required to drive the roll. Accordingly I propose to embody in a beating-engine of any type—that is, with any practical arrangement of circulating-channels—a beating-roll of comparatively small diameter to replace the large roll heretofore used, thereby obviating all of the objections as to power, friction, &c., which result from the use of a large roll. In order to obtain good circulation of the stock, I have omitted the backfall entirely and have provided means whereby the stock is delivered horizontally from the bottom of the roll, said means comprising a hood covering the roll and forming with the bottom of the channel a substantially horizontal feed-passage, through which the stock is fed to the roll, and a substantially horizontal delivery-passage, through which the stock is delivered from the roll. This construction obviates the necessity of lifting the stock over the backfall by the roll. The hood extends some distance below the center of the roll at the delivery side thereof and comes close to the outer edge of the disintegrating-blades. When now the roll is rotated rapidly to acquire the proper surface speed, the stock is drawn through the feeding-mouth by suction and delivered through the diverging delivery-mouth in a straight line, the action of the roll being somewhat similar to that of a centrifugal pump. In this construction the stock is delivered to the bottom of the channel, and is therefore kept properly agitated. The roll I have herein shown is provided with grooved longitudinal ribs, into which the disintegrating-blades are inserted, and is shown as being integral with its supporting-shaft. The roll and shaft may conveniently be made from a single casting.

Preferably I will employ two rolls, one in each channel, and the shafts supporting the rolls will extend clear across the pulp-tub, the shaft for one roll passing through the other channel between the hood and the inclined wing at the delivery side thereof, this construction serving to prevent the stock from coming in contact with the shaft.

Various other features of my improved beating-engine will be hereinafter described, and pointed out in the claims.

Figure 1 illustrates a side elevation of my improved engine. Fig. 2 is a longitudinal vertical section thereof through one of the circulating-channels. Fig. 3 is a top plan view. Fig. 4 shows a slightly-modified form of engine. Fig. 5 illustrates in detail the construction of my improved beating-roll. Fig. 6 is a vertical section of one side of the pulp-tub and shows the manner of vertically adjusting the rolls. Fig. 7 is a section on the line 7 7, Fig. 6. Figs. 8 and 9 are details showing different ways of preventing the stock from leaking around the shaft as it passes through the wall of the pulp-tub, and Fig. 10 is a view of my improved roll.

In Figs. 1 and 2 the pulp-tub is designated by 3, and it may be of any suitable shape or construction and is provided with the usual mid-feather 4, which divides the tub into the two circulating-channels 5 and 5'. Extending transversely across the tub and passing through suitable slots 7' in the side walls of the tub is the shaft 8, carrying the beating-roll 9, said roll being situated in one of the circulating-channels and having on its periphery blades 10, which coöperate with a bed-plate 11 of any suitable construction, situated in the bottom of the channel. The shaft 8 is supported in suitable bearings 19', which are vertically adjustable, as will be presently described. As seen in Fig. 2, the diameter of the beating-roll 9 is less than the depth of the channel, so that said beating-roll is entirely received by the channel. Extending entirely across the channel, between the mid-feather 4 and the side wall 4', and covering the upper portion of the roll, is a hood or bonnet 15 of a substantially semicircular shape, as shown in Fig. 2, the lower portion 16 of the bonnet at the delivery side of the roll being preferably shaped to fit and situated close to the ends of the blades in the roll, (see Fig. 2,) while the lower portion of the bonnet at the feeding side thereof may be situated some distance from the roll. Extending from the lower portion of the roll on either side thereof are upwardly-inclined wings 17 and 18, the wings 17 at the delivery side of the roll being stationary and being connected at its lower end to the lower point of the bonnet at 19'. The wings 17 and 18 form with the bottom of the channel a feeding mouth or passage 20 and a delivery mouth or passage 21, the said feeding-passage being converging, as shown, while the delivery-passage is preferably a diverging passage. With this construction it will be seen that as the roll is rotated to give the proper surface speed the stock will be freely drawn through the inlet or feed passage 20 by the action of the blades, and because the meeting edge 19, between the wing 17 and the bonnet, is closely adjacent the blades the stock is deflected from the roll and is delivered into the discharge-mouth 21, the lower portion 16 of the bonnet preventing any amount of stock from being carried over the roll by the blades.

That portion 13 of the bottom of the channel in front of and adjacent the bed-plate I have termed a "feed-apron," and the portion 14 of the bottom of the channel directly back of the feed-plate and over which the stock passes as it is delivered from the roll I have termed the "delivery-apron."

I will preferably so construct my feed-apron 75 13 and the delivery-apron 14 that they extend in a substantially horizontal direction, as shown, thereby omitting entirely the usual backfall, and when the aprons are constructed in this manner the hood and wings 80 will be so shaped that the meeting edges between the hood and wing on each side of the roll are some distance below the center of the roll, whereby the stock is fed to and delivered from the roll in a substantially horizontal direction.

Since the stock does not have to be lifted over the backfall by the roll, as in the ordinary beating-engine, but is instead drawn through the feed-passage 20 and delivered 90 in a straight line through the delivery-passage 21 by the rotation of the roll, my construction of beating-engine does not necessitate the expenditure of the power necessary to thus lift the stock over the backfall. 95

From the above it will be seen that my beating-roll is of such a size and so situated in the channel as to be substantially submerged in the stock. This feature of employing a submerged beating-roll, which is 100 situated entirely within the channel in which it operates, and the omission of the usual backfall, thus obviating the necessity of lifting the stock by the roller, I consider as one of the important features of my invention, for 105 the reason that I am enabled to obtain perfect circulation and disintegration of the stock with a minimum expenditure of power.

Since the stock is delivered from the roll in a substantially horizontal direction near 110 the bottom of the channel, the stock is kept agitated and is prevented from becoming clogged, as it frequently does where it is delivered over the backfall and at the top of the channel instead of the bottom thereof. 115 This agitation of the stock may be augmented by providing the channel at the delivery side of the roll with the scalloped portions or ruffles 23, such scallops or concavities as the stock is delivered thereover serving to give 120 the same a sort of boiling action. These ruffles may be placed either in the end of the apron 14 or partially in the apron and partially in the bed of the channel, as deemed best. 125

Preferably the delivery-passage 21 is provided with a parting-blade 60, the point of which comes, as shown, close to the periphery of the roll, such parting-blade dividing the delivery-passage into two channels and 130 serving to part the stock delivered, whereby it is still further agitated and mixed. The parting-blade 60, however, may be omitted, if desired.

I will preferably make the feed-apron 13 convex at its end and slightly concave as it approaches the bed-plate 11, as seen best in Fig. 2, and will give to the curved side 18' of the wing 18 such a shape that the central line of the converging feed-passage 20 is slightly inclined to the horizontal, this construction being found advantageous, because it allows the stock to be fed with greater facility, the converging shape of the feed-passage allowing the stock to be delivered to the roll without any clogging.

To regulate the amount of stock fed to the roll, I may, if desired, make my wing 18 at the feeding side of the roll in the form of a vertically-adjustable gate, which may be raised or lowered to admit more or less stock, as desired. I have illustrated in Fig. 2 one convenient form of gate, which is shown as being hollow and as having the curved side 18', which forms with the feeding-apron the delivery-mouth. The back side of the gate may be mounted to slide in suitable ways 24 on the mid-feather 4 and the side walls of the tub, respectively, and any suitable means may be employed for holding the gate in its adjusted position. Preferably the gate will be provided with suitable handles 25, by means of which it may be raised or lowered. By making the gate hollow, as illustrated, it is sufficiently buoyant so that even though it is made of iron it may be of substantially the same specific gravity as the stock in the channel, thus obviating the necessity of any counterbalancing means therefor.

My roll is preferably constructed as shown in Figs. 5 and 10, it presenting a solid core of metal having integral therewith the shaft 8, which supports the same. The periphery 40 of the roll is provided with a series of longitudinal ribs 27, in each of which is set a disintegrating-blade 10, the said ribs each having a suitable groove extending longitudinally thereof, into which the blade 10 is received, and said blade being held in place by any suitable means, such as tapering pins 29, which are driven through inclined apertures through the rib and blade, as seen in Fig. 5. I prefer this construction, because as 50 the inclined taper pins are driven into the apertures they operate to draw the blade tightly into its receiving-groove.

By using a metal roll having metallic ribs on its periphery, which receive the blades, I 55 do away with the necessity of employing wooden bars, between which the blades are clamped, as is the common construction, and I am enabled to use a blade of less width than can commonly be employed. Moreover, 60 the metal ribs 27 form firm supports for the blades. The roll will have any suitable number of blades, and between the ribs which support the blades the surface of the roll is grooved, as at 28, said grooves being 65 substantially U shape in cross section. This construction not only affords a means for firmly holding the blades in position, but

also allows of the use of narrower blades, for by forming the periphery of the roll with the grooves 28 between the blades the necessary 70 room is provided for the stock without making the blades as long as would be the case if the periphery of the roll were not grooved.

Since the blades I employ may be narrower than is commonly used, I may make them 75 also thinner without in any way rendering them less rigid or inflexible, thereby reducing the cost of the blades, which is quite an item in a machine of this type. Preferably the blades are of a uniform thickness, as 80 illustrated.

The purpose in making the grooves 28 substantially U-shaped is to avoid the presence of any sharp corners between the blades, into which the stock may become lodged. 85

One convenient way to make my roll is to make a casting of the proper shape, said casting including the cylindrical portion for the shaft 8 and the large cylindrical portion for the roll 9, and then planing out the 90 grooves 28 in a surface of the roll, to thereby leave the ribs 27. The ribs may then be grooved and bored for the reception of the disintegrating-blades.

To prevent the blades from chattering, 95 they are preferably inclined somewhat to the radial line, as shown in Fig. 5, such inclination being accomplished by making each blade parallel to a radial line a slight distance back of the blade, as seen in Fig. 5, 100 the blade *a* in said figure, for instance, being parallel to the dotted radial line *b*.

Where the stock is caused to circulate by suction, as in this device, more or less of a vacuum is created between the blades in 105 drawing stock through the feeding-passage, and unless said vacuum is destroyed it would be inclined to hold the stock between the blades, and thus carry the same over the roll. To prevent this, I may, if desired, provide 110 some means for admitting air between the blades of the roll, one convenient means for accomplishing this being to make the shaft hollow, as seen in Fig. 4, and to provide a series of radial air-ducts 30 extending from 115 said hollow shaft to the grooves 28 between the blades, such air-ducts admitting the air to the grooves 28, and thus destroying any vacuum which may be formed. I have three or more such air-ducts leading to each groove, 120 according to the length of the roll. As wear occurs between the roll and the bed-plate it is necessary to adjust the roll closer to the bed-plate, and I therefore mount my shaft 8 in vertically-adjustable bearings 19', which 125 are situated outside of the tub and are supported by a yoke-shaped stand 31. As illustrated, the said stand carries the bevel-gear 32, the shaft of which is journaled in the horizontal portion of the stand 31 and is screw-threaded into a suitable boss 33 upon the box or bearing 39, whereby the said bearing is suspended from the yoke. The bearing at each end of the shaft is supported in a simi-

lar manner, and to adjust the same simultaneously, so as to always maintain the roll in horizontal position, a shaft 34 extends across the tub and has thereon at each end bevel-gears 35, meshing with the bevel-gears 32, said shaft being supported in suitable bearings 37 and being operated by a suitable hand-wheel 36. By turning the hand-wheel 36 in either direction both ends of the shaft 8 will 5 be simultaneously raised or lowered, as will be obvious. Since the shaft projects through the slot 7' in the side walls of the tub, it is necessary to provide some means to prevent the stock from leaking around the shaft, and 10 this may be conveniently accomplished as illustrated in Figs. 8 and 9, wherein the stuffing-box 40, through which the shaft 8 passes and which is slidably mounted in the slot 7', is provided with the extended flange 41, which 15 is seated in a suitable recess in the side walls of the tub. If the side walls of the tub are of iron, I may provide a vertically-extending recess 42 on the inner face thereof, said recess being provided with vertically-extending 20 grooves which fit corresponding vertically-extending ribs 43 on the flange 41. This construction allows the stuffing-box 40 to be raised or lowered; but the zigzag line of contact between the flange 41 and the inside of the box 25 30 prevents any stock from leaking through, for owing to the consistency of the stock it cannot work past the ribs and grooves.

Where the flange 41 is on the inside of the wall of the tub, as in Fig. 8, I rely upon the 35 pressure of the pulp to hold it in place; but I may, if desired, tap the holding-bolts 44 into the flange 41, said bolts passing through a suitable slot 45 in the side walls of the tub, and provide said bolts with a suitable spring 40 46, which bears against the head of the same and against the tub, said springs and bolts operating to yieldingly hold the stuffing-box in place, but to allow it to be vertically adjusted. 45

In Fig. 9 I have shown a modified construction wherein the stuffing-box 40' is provided with the extended wings 41', which set in grooves centrally arranged in the side walls of the tub, the said flanges and grooves being 50 ribbed, as in the other construction.

It will be understood, of course, that when the construction shown in Fig. 9 is employed the slot 7' in the side of the pulp-tub, through which the stuffing-box for the shaft projects, 55 will extend clear to the top of the tub.

In one embodiment of my invention I will employ two disintegrating-rolls, there being one such roll in each of the circulating-channels, and, as illustrated in Figs. 2 and 3, the 60 shafts for the rolls will be situated in the same horizontal plane and will be so placed that the shaft 8 of the roll in the channel 5' will pass through the channel 5 between the hood and the wing 17, as seen in Fig. 2. By this 65 construction the stock is prevented from contacting with the shaft of the roll.

Preferably the two rolls will be driven from

the same driving mechanism and each shaft will have on the end thereof suitable gears 48, which mesh with each other, one of said 70 gears being connected to and driven by a suitable driving-pulley 49. By this system of gears the shafts are rotated in opposite directions, but in the appropriate directions to cause the stock to circulate, as indicated by 75 the arrows in Fig. 3.

By using two rolls in the same tub the stock may be disintegrated more rapidly than where one roll is used, and because of my peculiar construction less power is expended in driving the engine. Moreover, because the rolls employed are comparatively small sufficient 80 space is afforded in each of the channels so that, if desired, a washing-cylinder may be placed therein, which construction would not 85 be possible where the rolls are of the large diameter without unduly increasing the size of the pulp-tub.

Another advantage which I obtain by employing two beating-rolls is that my beating- 90 engine becomes a universal engine—i. e., it may be fed from either direction—and it is not necessary, therefore, to make the engines either right-hand or left-hand engines, according to the space in which they are used, 95 as is the case with the present existing styles of engines.

In Fig. 4 I have illustrated a slightly-modified form of engine wherein the mid-feather 4' is horizontally arranged, thus dividing the 100 tub into two circulating-channels 5^a and 5^b, which are arranged one above the other. In other respects, however, the apparatus is the same as that in the other views, and I employ the roll of less diameter than the depth 105 of the channel and use a hood device, as in my former modification.

Although I have herein illustrated my comparatively small beating-roll as situated entirely in the circulating-channel—that is, 110 with no portion thereof projecting above the channel—yet I do not desire to be limited to this precise arrangement, as my broad invention would not be departed from if a roll of 115 small diameter were so placed in the channel that a portion thereof extended above the top of the mid-feather or if in conjunction with any roll operating in said channel a hood was used which covered the upper portion of the roll and formed, with the bottom of the channel, a substantially horizontal delivery-passage, so that the stock would be delivered 120 from the bottom of the roll in a substantially horizontal direction, and therefore although I have herein shown the best form now known 125 to me of embodying my invention, yet I wish it understood that the details thereof may be varied in many particulars without departing from the spirit and scope of my invention as expressed in the following claims. 130

Having fully described my invention, what I claim as new, and desire to secure by Letters Patent, is—

1. In a beating-engine, a pulp-tub having a

longitudinally - extending circulating - channel, a disintegrating - roll situated entirely within said channel intermediate its ends, and means to direct the entire quantity of stock 5 beneath the roll, said roll having a horizontal discharge at the bottom of the channel.

2. In a beating-engine, a pulp-tub having a substantially flat bottom circulating-channel, a disintegrating - roll situated within said 10 channel intermediate its ends, said roll being of such size that its axis is below the normal level of the stock in the channel, a feed-passage through which the stock is fed to the roll, and a delivery-passage through which the 15 stock is delivered from the roll, said delivery-passage having a horizontal direction and being situated at the bottom of the channel.

3. In a beating-engine, a pulp-tub having a vertical mid - feather dividing the tub into 20 two circulating-channels, the bottom of each of said channels being substantially flat, a disintegrating-roll situated entirely within one of said channels intermediate its ends, and a hood covering the upper portion of the roll 25 and forming with the flat bottom of the channel passages to feed the stock to and deliver it from the roll in a substantially horizontal direction.

4. In a beating-engine, a pulp-tub having a 30 circulating-channel, a disintegrating-roll operating in said channel, a hood covering the upper portion of the roll and forming with the bottom of the channel a substantially horizontal delivery-passage whereby the stock 35 is delivered from the bottom of the roll in a substantially horizontal direction.

5. In a beating-engine, a pulp-tub having a substantially flat bottom, and provided with a vertical mid-feather dividing the tub into 40 two circulating - channels, a disintegrating - roll situated entirely within one of said channels intermediate its ends, a horizontally-arranged feed-passage through which the stock is fed to the roll, and a horizontally-arranged 45 delivery-passage through which the stock is delivered from the roll.

6. In a beating-engine, a pulp-tub having a mid-feather dividing the tub into two circulating-channels, a disintegrating-roll situated 50 entirely in one of said channels intermediate the ends of the latter, said roll being of such a size as to be below the normal level of the stock in the channel, and a hood covering the upper portion of the roll and forming 55 with the bottom of the channel passages to feed the stock to and deliver it from the bottom of the roll in a substantially horizontal direction.

7. In a beating-engine, a pulp-tub having 60 substantially flat-bottomed circulating-channels communicating with each other, a disintegrating-roll in each channel between its ends, a hood covering the upper portion of each roll, said hoods forming with the bottoms of the circulating - channels substantially horizontal delivery - passages for the stock, whereby the stock is delivered from

the bottom of each roll in a substantially horizontal direction.

8. In a beating-engine, a pulp-tub having a 70 mid-feather forming two parallel circulating-channels, a pair of shafts extending across the tub, a disintegrating-roll on each shaft, said rolls being of less diameter than the depth of said channels and being situated in different 75 channels, a hood covering the upper portion of each roll and having an upwardly-inclined wing extended from the bottom thereof at the delivery side of the roll, the shafts being so situated relative to each other that each shaft 80 passes through the space between the hood and the wing of the roll on the other shaft, whereby the shafts are protected from contact with the stock.

9. In a beating-engine, a pulp-tub having a 85 vertical mid-feather dividing the tub into two circulating - channels, a bed - plate in each channel, the bottom of said channels extending back from said bed-plates in a substantially horizontal direction, two shafts extending 90 across the tub below the normal level of the stock in said channels, a disintegrating-roll on each shaft, one roll being situated in each channel, and means to direct all of the stock under each of said rolls, said stock being delivered from the rolls in a substantially 95 horizontal direction.

10. In a beating-engine, a pulp-tub having a circulating-channel, a disintegrating-roll situated in said channel, a hood extending 100 across said channel and covering the upper portion of the roll, said hood having inclined wings extending upwardly from the lower portion thereof to form with the bottom of the channel a converging feed and a horizontal 105 diverging delivery passage for the stock.

11. In a beating-engine, a pulp-tub having a circulating-channel therein, a disintegrating-roll situated entirely in said channel, said roll being so situated and being of such a size 110 as to be below the level of the stock, a hood extending across the channel and covering the upper portion of the roll, the lower portion of said hood coming close to the periphery of the roll on the delivery side thereof 115 and extending below the center of the roll, and an upwardly-inclined wing connected to the hood to form a diverging delivery-passage for the stock.

12. In a beating-engine, a pulp-tub having 120 a substantially flat - bottomed circulating-channel, a disintegrating - roll situated entirely in said channel, a hood covering said roll and extending below the center thereof, and an upwardly-inclined wing connected to 125 the lower portion of the hood on the delivery side of the roll, such lower portion of the hood being situated close to the periphery of the roll whereby stock is prevented from being carried over the roll.

13. In a beating-engine, a pulp-tub having 130 a circulating-channel, a disintegrating-roll in said channel, a hood extending across the channel and covering the roll, an upwardly-

- inclined wing connected to the hood at the delivery side of the roll and forming a diverging discharge-passage for the stock, and a parting-blade in said discharge-passage.
- 5 14. In a beating-engine, a pulp-tub having a flat-bottomed circulating-channel, a disintegrating-roll in said channel, said roll being of such a size and so situated as to be below the level of the stock in the channel, a hood covering the upper portion of said roll, the lower portion of said hood at the delivery side of the roll being situated close to the periphery of the roll, and on the feed side of the roll being spaced from the roll.
- 10 15. In a beating-engine, a pulp-tub having a circulating-channel, a disintegrating-roll situated entirely within the said channel, a bed-plate in the bottom of the channel intermediate its ends, the bottom of the channel extending backwardly from the plate in a substantially horizontal direction, and a hood covering the roll and forming with the channel bottom feed and delivery passages for the stock, the roll being of such a size that 15 its axis is situated below the level of the stock.
16. In a beating-engine, a pulp-tub having a circulating-channel, a disintegrating-roll in said channel, a bed-plate in the bottom of the channel intermediate its ends, a delivery-apron forming part of the bottom of the channel and extending back from the bed-plate in a substantially horizontal direction, and a hood covering said roll and forming with the channel bottom feed and delivery passages for the stock, the roll being of such a size that its axis is situated below the level of the stock, and the stock in its circulation all passing beneath the hood.
- 20 17. In a beating-engine, a pulp-tub having a substantially flat-bottomed circulating-channel, a disintegrating-roll in said channel, a hood covering the upper portion of the roll and extending below the center thereof, upwardly-inclined wings connected to the lower portion of the hood at each side thereof, a bed-plate and delivery and feed aprons extending therefrom in an approximately horizontal direction, said aprons and wings forming a converging feed and a diverging delivery passage, and means to rotate the roll whereby the stock is drawn through the roll by suction.
- 25 18. In a beating-engine, a pulp-tub having a circulating-channel, a disintegrating-roll in said channel, a hood covering the upper portion of the roll and extending below the center thereof, upwardly-inclined wings connected to the lower portion of the hood at each side thereof, a bed-plate, and delivery and feed aprons extended therefrom in an approximately horizontal direction, said aprons and wings forming a converging feed and a diverging delivery passage, the wing at the 30 feed side of the roll being vertically adjustable to regulate the feed of the stock, and means to rotate the roll whereby the stock is caused to circulate by suction.
19. In a beating-engine, a pulp-tub having a circulating-channel, a vertically-adjustable shaft passing through slots in the sides of the tub and having a disintegrating-roll thereon, stuffing-boxes in said slots, said stuffing-boxes having ribbed flanges extending therefrom and sliding in correspondingly-shaped recesses in the tub-walls.
- 70 20. In a beating-engine, a pulp-tub having slotted walls, a vertically-adjustable shaft projecting through said slots and having a disintegrating-roll thereon, vertically-adjustable stuffing-boxes in said slots and through which the shaft passes, said stuffing-boxes each having a flange projecting therefrom which is received in a recess in the walls of the tub, vertical ribs on said flanges, and corresponding grooves in said recesses, whereby the stock is prevented from leaking.
- 80 21. In a beating-engine, a pulp-tub having a mid-feather dividing the tub into two circulating-channels having bed-plates, the bottom of said channels extending back from said bed-plates in a substantially horizontal direction, a pair of shafts extending horizontally across the tub and projecting outside thereof, a disintegrating-roll on each shaft, said 85 rolls being in different channels and each of said rolls being of such a size and so situated in its channel as to be below the level of the stock, gearing connecting said shafts together whereby they may be rotated in unison, and 90 means to direct the stock beneath the rolls.
- 90 22. In a beating-engine, a pulp-tub having a mid-feather dividing the tub into two circulating-channels, a pair of shafts extending horizontally across the tub and projecting outside thereof, a disintegrating-roll on each shaft, said 95 rolls being in different channels, and gears on said shafts outside the tub and meshing with each other, whereby the rolls may be rotated in unison and in opposite directions.
- 105 23. In a beating-engine, a pulp-tub having a mid-feather dividing the tub into two circulating-channels, a pair of shafts extending horizontally across the tub and projecting outside thereof, a disintegrating-roll on each shaft, said 110 rolls being situated in different channels and each being of a diameter less than the depth of the channel, gears on said shafts outside the tub, said gears meshing 115 with each other, and means to rotate one of said gears whereby the rolls are rotated in unison and in opposite directions.
- 120 24. In a beating-engine, a pulp-tub having a circulating-channel, a disintegrating-roll therein, and means to direct the stock beneath the roll, said roll having blades on its periphery and means to admit air between said blades whereby the stock is freely delivered.
- 125 25. In a beating-engine, a pulp-tub, a disintegrating-roll, a bed-plate coöoperating there-

with, a delivery-apron extending from the bed-plate in a substantially horizontal direction, a hood covering said roll and provided with an upwardly-inclined wing to form with 5 the delivery-apron a diverging discharge-passage, and means to admit air between the blades of the roll whereby the stock is freely delivered.

26. A roll for a beating-engine, presenting 10 a cylindrical body of metal having longitudinal grooved metallic ribs on its periphery, disintegrating-blades set into said grooves, and pins extending diagonally through the ribs and blades and serving to hold said blades 15 in place.

27. A roll for a beating-engine presenting 20 a cylindrical metallic body provided on its surface with ribs extending longitudinally thereof, said ribs being grooved and disintegrating-blades secured in said grooves.

28. A roll for a beating-engine, comprising a body portion formed from a single piece of metal, and disintegrating-blades secured to

the periphery of the body portion, the body being grooved out between the blades. 25

29. In a beating-engine, a pulp-tub having a circulating-channel, a disintegrating-roll in said channel, and a delivery-passage through which the stock is delivered from the roll, said passage being divided into a plurality of 30 channels.

30. In a beating-engine, a pulp-tub having a circulating-channel, a disintegrating-roll in said channel, a diverging delivery-passage through which the stock is delivered from the 35 roll and a horizontally-arranged parting-blade extending across the delivery-passage and dividing the same into two channels.

In testimony whereof I have signed my name to this specification in the presence of 40 two subscribing witnesses.

MELVIN A. MILLS.
